(57) **CLAIM**

We claim the ornamental design for an adjustable height caster, as shown and described.

DESCRIPTION

FIG. 1 is a left side view of an adjustable height caster.

FIG. 2 is a front view of the design shown in FIG. 1.

FIG. 3 is a right side view of the design shown in FIG. 1; and,

FIG. 4 is a rear view of the design shown in FIG. 1.

The broken line showing of elements of a caster are for illustrative purposes only and form no part of the claimed design.

The undisclosed top and bottom views are not part of the claimed design.
